UNITED STATES PATENT OFFICE.

MARTIN HUBBE, OF BAYONNE, NEW JERSEY, ASSIGNOR OF ONE-HALF TO
GEORGE H. REYNOLDS, OF NEW YORK, N. Y., AND MARCUS A. HARDY,
OF NEWPORT, RHODE ISLAND.

SUBMARINE TORPEDO-BOAT.

SPECIFICATION forming part of Letters Patent No. 243,907, dated July 5, 1881.

Application filed February 24, 1879.

To all whom it may concern:

Be it known that I, MARTIN HUBBE, of Bayonne, in the county of Hudson and State of New Jersey, have invented certain new and useful Improvements in Marine Vessels, of which the following is a specification.

My invention relates particularly to submarine vessels, and especially to submarine torpedoes, propelled by a motive agent contained within them and steered and controlled from the shore or other place or vessel. Its object is to preclude the fouling of the cable with the rudder or propeller-wheel as it is paid out.

To this end it consists in a torpedo-vessel having a pipe or tube for the cable connected with the cable-coil chamber and extending beyond or aft the rudder and propeller-wheel.

In the accompanying drawings, Figure 1 represents a partly-sectional side view of the rear or stern portion of the propeller-vessel and appurtenances embodying my invention, and Fig. 2 is a central longitudinal vertical section of a modification of the same.

Similar letters of reference designate corresponding parts in both figures.

A, Figs. 1 and 2, represents the rear or stern portion of the hull of a movable torpedo-boat provided with a propeller-wheel, P.

B designates the after bulk-head of the cable-coil compartment.

D is the drum or case in which the cable, preferably in the form of a coil, is carried.

C, Fig. 1, is a tube, preferably tapering rearwardly, which leads from the bulk-head D aft and diagonally down to the bottom of the hull.

A. It has at the ends a water-tight connection with the bulk-head B and hull A, respectively.

E is a sliding mouth-piece, attached to the

center-piece of the drum D and communicating with the tube C. Outside the bottom of the hull A an extension-tube, F, is attached to the tube C and leading along the skeg G, as also underneath the rudder R and propeller-wheel P. It enables the cable W to pay out aft of the rudder and wheel, and precludes its being carried into or fouled with the same.

In torpedoes where the propeller-wheel shaft M is driven by gearing S, as in Fig. 2, the shaft may be hollow and receive within it a stationary pipe, X, leading through it and out aft the propeller-wheel. The inboard end of the shaft M will in such cases be provided with a stuffing-box, Z, to prevent water from entering the torpedo. The conical tube C, in this modification of my invention, instead of leading diagonally down, passes directly from the bulk-head B to pipe X, and is secured to the same with a water-tight connection, thus establishing a nearly straight tube for paying out.

What I claim as my invention, and desire to secure by Letters Patent, is—

1. A torpedo-vessel having a tube for the cable connected with the cable-coil chamber and extending beyond or aft the rudder and propeller-wheel, substantially as specified.

2. A torpedo-vessel having a tube for the cable connected with the cable-coil chamber, extending diagonally downward through the hull of the vessel, and provided with an extension leading underneath the rudder and propeller-wheel, substantially as specified.

MARTIN HUBBE.
